UNITED STATES PATENT OFFICE

LUTHER E. MORRISON, OF NEW YORK, N. Y., ASSIGNOR TO MERGENTHALER LINOTYPE COMPANY, A CORPORATION OF NEW YORK

TYPOGRAPHICAL COMPOSING AND CASTING MACHINE

Application filed September 13, 1929. Serial No. 392,359.

This invention relates to typographical machines, such as linotype machines of the general organization presented in Letters Patent of the United States to O. Mergenthaler, No. 436,532, wherein circulating matrices are released under the control of a keyboard from a magazine in the order in which their characters are to appear in print and then composed in line in an "assembling elevator", the composed line then transferred through an intermediate channel into a vertically movable "first elevator" which presents it to a mold, whereupon the mold is filled with molten metal to form a slug or linotype against the matrices which produce the type characters thereon, and the matrices thereafter elevated and returned through a distributing mechanism to the magazine from which they started. More particularly, it relates to that class of machines designed to handle matrices provided with two or more superposed characters, and wherein the assembling elevator, intermediate channel, and first elevator are each provided with two sets of supporting rails whereby the matrices may be composed and maintained at an upper or lower level, or both, as desired, to locate the selected characters in operative position. When it is desired to cast a slug from the lower characters of all of the matrices of a composed line (as for a "solid" line of italics), it is the usual practice to assemble and maintain such matrices, not at the upper level as would otherwise be required, but at the lower level, and then to arrest the first elevator in a slightly raised position so as to locate the selected characters opposite the mold slot, such arrest of the elevator being ordinarily effected by a stop member mounted on the vise frame and adapted to be thrown into action at the will of the operator. Similarly, in the use of "head-letter" matrices or matrices with characters above 14 pt. the same practice is followed so as to effect the proper alinement of the matrix characters with the mold slot. The foregoing practice has given rise to very serious objections, as it frequently happens that an operator, through oversight or carelessness, will as-

semble matrices at the upper level while the elevator stop is in action, which will result in the improper presentation of the matrix line to the mold and hence produce a "squirt", or cause damage to the parts, or both.

The present invention is intended to overcome the above objection and contemplates means for preventing the composition of matrices except under the proper conditions. To this end, specifically, the machine is equipped with a keyboard lock which is normally inoperative but which will be rendered operative automatically whenever an attempt is made to compose matrices at the upper level in the assembler when the stop is set to arrest the first elevator in a raised position before the mold.

In the embodiment illustrated, the keyboard lock is in the form of a long bar which is arranged to be moved into and out of locking engagement with the series of key-actuated slides which control the operation of the customary cam yokes employed for operating the escapement reeds which effect the release of the matrices from the magazine. This locking bar is operated through a train of connections by a fore-and-aft actuating member disposed behind an extension on the assembled rail which determines the level at which the matrices are composed in line. The relative disposition of the assembler rail and the locking-bar actuating member is such that normally the rail may be moved into and out of the assembler as desired without affecting the actuating member, but when the first elevator stop is brought into use, it automatically positions between the actuating member and the assembler rail (if the latter is withdrawn at the time) a rod or interponent which will cause the rail, as it is shoved into the assembler, to push the actuating member rearwardly and move the keyboard locking bar into its locking position, thereby preventing the release of matrices from the magazine and consequently preventing their delivery to or composition in the assembler. If at the time the first elevator stop is brought into use the assembler rail occupies its active position within the

assembler, the same locking action will take place, since the rod or interponent connected to the first elevator stop is itself designed under such conditions to move the actuating member rearwardly and effect the locking of the keyboard.

It will be seen therefore that according to the foregoing arrangement of the parts, the keyboard will be locked whenever the first 10 elevator stop and the assembler rail are both in their active position, which is the condition giving rise to the objections before noted,—the actuation of the keyboard lock being effected automatically by the movement of either the stop or the rail to active 15 position while the other is in active position. On the other hand, when the first elevator stop and the assembler rail are in inactive position, or one of them only in active position, 20 at the time, the keyboard lock will be inoperative or ineffective and the matrices may be released from the magazine and composed in line in the regular way, whether at the upper level or the lower level as required.

25 While it is preferred to make use of an automatic keyboard lock as above described, it is within the contemplation of the invention to prevent the composition of the matrices by resorting to other well known expedients, as for instance by locking the matrices in the magazine or by locking against actuation the matrix releasing escapements or their operating reeds. This can easily be 30 done by connecting the actuating member (which in the illustrated embodiment operates the keyboard locking bar) to a matrix lock or an escapement lock or an escapement reed lock, as the case may be, so as to operate such lock in the same way and under the 35 same conditions as the keyboard lock described.

As a further expedient, the actuating member could be connected to a shift frame such as is sometimes employed for moving the escapement reeds into and out of engaging relation to the matrix releasing escapements. In this instance, as in the others given, the release of matrices from the magazine would be prevented even though the keyboard mechanism itself were not locked against actuation.

It is also within the contemplation of the invention to prevent the composition of the matrices without actually preventing their release from the magazine, as for instance by connecting the actuating member above mentioned to a clutch or similar device which would arrest the operation of the well known assembler belt or the operation of the driving means for the entire assembling mechanism.

60 The actuating member, because of the manner in which it is operated, lends itself readily to these and other adaptations, and since any mechanic skilled in the art could

easily make them without further directions, it has not been thought necessary to illustrate them in the drawings. Indeed, in another aspect of the invention, the actuating member could be made to operate a safety device 70 in the form of an alarm or signal to warn the operator when the parts are in improper relative adjustment.

It will be understood therefore that the invention is not limited to any specific form or 75 embodiment, except insofar as such limitations are specified in the appended claims.

Referring to the drawings:

Fig. 1 is a perspective view of portions of 80 a linotype machine equipped with the present improvements;

Fig. 2 is a detail fragmentary plan view of 85 the first elevator stop or filler piece and the connected rod or interponent;

Fig. 3 is a section taken on the line 3—3 85 of Fig. 2;

Fig. 4 is a vertical section taken through 90 the keyboard mechanism and the assembler, showing in particular the connections between the keyboard locking bar and the actuating member therefor;

Fig. 5 is a rear elevation of a portion of 95 the keyboard locking bar; and

Figs. 6, 7, and 8 are enlarged plan views, 100 in the nature of diagrams, showing the assembler rail and the rod or interponent connected to the first elevator stop as well as the actuating member for the keyboard lock 105 in different relative positions.

The matrices X (herein shown as of the two-letter variety) are released from their storage magazine (not shown) by means of the escapement actuating reeds 1 which are operated by the pivoted cam yokes 2 under the control of the finger keys 3. The yokes 2 are equipped with the rotary cams 4 which are normally held at rest by the engagement of the stop pins 5 thereon with the fixed abutments 6, but when the finger keys are actuated, the yokes are tripped by the triggers 7 and the cams 4 allowed to fall into engagement with the underlying power-driven rolls 8, which then rotate the cams and cause them to rock the yokes 2 upwardly for the operation of the escapement reeds. The triggers 110 7 are operated from the finger keys as usual through the medium of the vertical slides 9, which rise in tripping the cam yokes and later fall by gravity to return the triggers to their original position in time to support the cam yokes after they have completed their operation of the escapement reeds and stop the rotation of the cams 4. These parts and their mode of operation are so well known 115 that any further description would be superfluous.

The matrices X, as they are released from their storage magazine, are composed in line 120 within the assembler or assembling elevator A in the usual way. After composition of 125

the line, the elevator A is raised into registration with the intermediate channel B, through which the line is transferred into the transporter or first elevator C. The first elevator then descends to locate the composed line before the casting mold (not shown), which immediately advances from the rear into engagement with the line for the casting operation. The assembling elevator A is formed with a pair of fixed matrix supporting rails A¹ and with an adjustable matrix supporting rail A², the adjustment of the latter being effected by means of a handle A⁴ fast to a rock shaft A³ carried by the elevator and connected to the rail through arms A⁵. The adjustable rail A² thus determines the level at which the matrices are composed in line, said rail acting when in active position to sustain the matrices at the upper level and when in inactive position to allow them to pass to the lower level where they are sustained by the fixed rails A¹. The first elevator C (Fig. 1) is likewise formed with a pair of fixed rails to sustain the matrices at the lower level and with a retractable rail to sustain them at the upper level. The intermediate channel B is formed with two pairs of fixed rails B¹ and B², respectively, which serve to maintain the matrices at their composed levels during the transfer of the line from one elevator to the other. The foregoing parts are well known, but if further information is desired, reference may be had to the Rogers Reissue Patent No. 13,489.

In the normal operation of the machine, the first elevator C is allowed to descend to its lowermost position, as determined by the engagement of its set screw C³ with the top of the vise frame G. In this connection, it is pointed out that the elevator is also provided with a second set screw C⁴ arranged to engage and depress the so-called "vise-automatic" G¹ as the elevator comes to rest. The operation of the vise-automatic is fully described in the Mergenthaler Patent No. 436, 532 before referred to, so that no detailed description thereof seems necessary, but it may be noted that unless it is depressed by the first elevator, the operation of the machine will be arrested almost immediately and the casting operation thereby prevented, due to the automatic disengagement of the main driving clutch.

For reasons previously noted, it is sometimes desired to arrest the first elevator in a raised position with reference to the mold, and this may be effected, as customary, by means of a stop or filler piece E pivoted, by means of a rock-shaft E¹, to a block G² on the vise frame G so as to be swung into or out of active position. At its free end, the stop is provided with two contact pieces E² and E⁴, the former being carried directly by the body portion of the stop and adapted to cooperate with the set screw C³ in limiting the descent of the elevator, and the latter being carried by a hinged flap or section E³ and adapted to cooperate with the set screw C⁴ in depressing the vise automatic G¹. In Fig. 1, the stop or filler piece E is shown in active position and hence will bring about the arrest of the first elevator in its raised position, as well as the depression of the vise automatic G¹, in the usual way. When the elevator is thus arrested, it is necessary that the matrices stand at the lower level, as otherwise the objections before mentioned will arise.

According to the present invention, as above stated, means are provided for automatically locking the keyboard against actuation when both the elevator stop E and the assembler rail A² are in active position, so as in this way to prevent the release of matrices from the magazine, and consequently their composition in line, at a time when said parts are in improper relative adjustment.

The locking device proper is in the form of a long bar F extending across the entire series of key-actuated slides 9 and movable into and out of locking engagement with the customary shoulders 9^a presented by the slides near the top. In the present instance, the locking bar F is attached at its opposite ends to a pair of arms F¹, fast to an overlying rock shaft F² journaled in brackets F³ fixed to the keyboard frame (see Fig. 5). At the left, (looking from the front of the machine), the shaft F² is extended beyond its supporting bracket and is provided at its extremity with an operating arm F⁴, which latter is connected by a long link F⁵ to one (the horizontal) arm of a bell-crank lever F⁶, whose other (the vertical) arm is connected to a fore-and-aft actuating member J.

The bell-crank lever F⁶ and the actuating member J are both supported at the lower end of the intermediate channel B, the lever being centrally pivoted thereto, as at F⁷, and the actuating member being slidable endwise in suitable guides J¹. A spring F⁸, pulling downwardly on the rock shaft arm F⁴ from a fixed part of the frame, tends constantly to hold the locking bar F in its unlocking position as shown in the drawings, the actuating member J in this position of the locking bar keeping its forward position, as indicated in Figs. 6 and 8.

It may here be noted that the actuating member J is located in the horizontal plane of the adjustable assembler rail A², and that the latter is formed with a leftward extension A⁶ adapted at times to push the member J toward the rear and, through its connections with the locking bar F, to move the latter into locking engagement with the key-actuated slides 9. The rail extension A⁶ is beveled off at its rear corner, as at A⁷, to provide a cam surface for a purpose presently to be described.

As best shown in Figs. 2 and 3, the rock

shaft E¹ of the first elevator stop or filler piece E is extended forwardly to provide a turning handle E⁵, and at the rear it has fast thereto a small crank arm E⁶ provided with 5 a rearwardly extending crank pin E⁷. This crank pin E⁷ plays in a vertical elongated slot H¹ of a long bar or rod H extending to the right across the vise frame G and terminating in engagement with the actuating 10 member J, which latter presents a broad flat engaging face J² at the front to maintain engagement with the rod at all times.

The bar H is slideable longitudinally on the vise frame, being guided in its movements by a grooved block G⁸ thereon, and at 15 the right it is formed with a hinged section H² supported in a pair of brackets B⁹ on the intermediate channel B. This hinged section H², in addition to its endwise movement, is 20 capable of a swinging motion forwardly and backwardly in the supporting brackets B⁹ so as to push the actuating member J toward the rear under certain conditions; and moreover, it is beveled off at its forward corner, 25 as at H³, to provide a cam surface adapted to cooperate with the cam surface A⁷ of the assembler rail A².

The action of the parts will now be clear: Assuming for example that it is desired to 30 cast a solid line of italics, or a line of head-letter characters, the operator will, if necessary, move the assembler rail A² to its forward or inactive position in order to allow the matrices to be composed at the lower level in 35 the assembler and will also swing the stop E into active position in order to arrest the first elevator in its raised position. This is the condition represented in Fig. 1, and since the setting of the parts is correct, the composition 40 of the line may proceed, the locking bar F being maintained by the spring F⁸ in its unlocking position as shown. In this condition of the parts, the actuating member J occupies its forward position as shown by the full 45 lines in Fig. 6, while the hinged section H² of the rod H occupies its rightmost position as indicated by the dotted lines in said figure, having been moved to that position by the turning of the crank arm E⁶ at the time the 50 stop E was swung into active position by the turning of the handle E⁵ on the rock shaft E¹.

If now the operator, through carelessness or otherwise, should move the assembler rail A² rearwardly into active position (which 55 would allow the matrices to be improperly composed at the upper level in the assembler), the rail in partaking of such movement will, because of the interposition of the hinged section H², push the actuating rod J to the 60 rear, as shown in Fig. 7, and thereby move the locking bar F above the shoulders 9^a of the slides 9 and thus prevent the actuation of the keyboard. No harm can therefore result, since the release of the matrices from 65 their storage magazine is prevented, and the

composition cannot proceed until the assembler rail is withdrawn to its forward inactive position or until the first elevator stop is turned back to its inactive position. The choice will depend upon the nature of the 70 next line to be composed.

If the assembler rail A² should be in its forward or active position (as shown by the full lines in Fig. 8) at the time the first elevator stop E is swung into active position (which would also create the objectionable condition above mentioned), the hinged section H², in moving to the right, will bring its cam surface H³ into engagement with the cam surface A⁷ of the assembler rail, and these cam surfaces by their mutual engagement will swing the hinged section H² of the rod H rearwardly and push the actuating member J before it (as indicated by the dotted lines in Fig. 8) thereby moving the 75 locking bar F to its locking position. In this latter case, as before, the composition of the 80 matrices cannot proceed until the parts are properly adjusted, either by withdrawing the assembler rail to inactive position or by throwing the first elevator stop out of action.

In short, it will be found that the keyboard is automatically locked whenever the first elevator stop E and the assembler rail A² are 85 both in active position, the locking of the keyboard being effected by the movement to the rear of the actuating member J when either of said parts is moved to active position while the other is in active position. On the other hand, when both the first elevator 90 stop and the assembler rail are in inactive position, or either one in inactive position while the other is in active position, the keyboard (due to the action of spring F⁸) will be maintained in unlocked condition to permit 95 the composition of the matrices in the regular way. While it is not generally customary to compose a whole line of matrices at the 100 upper level in the assembler when the first elevator stop is out of action, no harm can result if this is done, because the first elevator in being allowed to descend to its lower level will present the line properly before the 105 mold.

As before stated, the invention has been 110 shown herein only in preferred form and by way of example, and many modifications and alterations will readily suggest themselves to those skilled in the art without departing from the spirit of the invention or without 115 avoiding the scope of the appended claims.

Having thus described my invention, what I claim is:

1. In a typographical composing and casting machine, the combination of means for 120 composing matrices at different levels, means for presenting the composed matrices at different levels to the mold, and automatic means for preventing the composition of the 125 matrices except when the first two said means 130

are set in proper cooperative relation to each other.

2. In a typographical composing and casting machine, the combination of an adjustable member to determine the level at which the matrices are composed, an adjustable member to determine the level at which the composed matrices are presented to the mold, and automatic means for preventing the composition of the matrices in the event of the improper relative adjustment of the two said members.

3. In a typographical composing and casting machine, the combination of an adjustable member to determine the level at which the matrices are composed, an adjustable member to determine the level at which the composed matrices are presented to the mold, and means actuated by one of said members for preventing the composition of the matrices in the event of their improper relative adjustment.

4. In a typographical composing and casting machine, the combination of an adjustable member to determine the level at which the matrices are composed, an adjustable member to determine the level at which the composed matrices are presented to the mold, and means actuated by either of said members for preventing the composition of the matrices in the event of their improper relative adjustment.

5. In a typographical composing and casting machine, the combination of an assembler provided with a matrix supporting rail adjustable to active or inactive position, a vertically movable transporter adapted to receive the composed matrices from the assembler and present them to the mold, a stop or filler piece adjustable to active or inactive position so as to arrest said transporter in raised position or permit it to descend to its normal position, and automatic means for preventing the composition of the matrices when both the matrix supporting rail and the stop or filler piece are in active position.

6. In a typographical composing and casting machine, the combination of means for releasing matrices from their storage magazine, means for composing the released matrices at different levels, means for presenting the composed matrices at different levels to the mold, and automatic means for preventing the release of matrices from the magazine except when said matrix composing and said matrix presenting means are set in proper cooperative relation to each other.

7. In a typographical composing and casting machine, the combination of means for releasing matrices from their storage magazine, an adjustable member to determine the level at which the released matrices are composed, an adjustable member to determine the level at which the composed matrices are presented to the mold, and automatic means for locking the keyboard mechanism against actuation in the event of

preventing the release of matrices from the magazine in the event of the improper relative adjustment of the two said level determining members.

8. In a typographical composing and casting machine, the combination of means for releasing matrices from their storage magazine, an assembler wherein the released matrices are composed in line and provided with a matrix supporting rail adjustable to active or inactive position in determining the lever at which the matrices are composed, a vertically movable transporter adapted to receive the composed line from the assembler and present it to the mold, a stop or filler piece adjustable to active or inactive position so as to arrest said transporter in a raised position or permit it to descend to a normal lower position, and automatic means for preventing the release of matrices from the magazine when both the matrix supporting rail and the stop or filler piece are in active position.

9. In a typographical composing and casting machine, the combination of means for releasing matrices from their storage magazine, an assembler wherein the released matrices are composed in line and provided with a matrix supporting rail adjustable to active or inactive position in determining the level at which the matrices are composed, a vertically movable transporter adapted to receive the composed line from the assembler and present it to the mold, a stop or filler piece adjustable to active or inactive position so as to arrest said transporter in a raised position or permit it to descend to a normal lower position, and means for preventing the release of matrices from the magazine when both the matrix supporting rail and the stop or filler piece are in active position, said means being actuated by the movement of one of said parts to active position while the other is in active position.

10. In a typographical composing and casting machine, the combination of a keyboard mechanism for releasing matrices from their storage magazine, means for composing the released matrices at different levels, means for presenting the composed matrices at different levels to the mold, and automatic means for locking the keyboard mechanism against actuation except when said matrix composing and said matrix presenting means are set in proper cooperative relation to each other.

11. In a typographical composing and casting machine, the combination of a keyboard mechanism for releasing matrices from their storage magazine, an adjustable member to determine the level at which the released matrices are composed, an adjustable member to determine the level at which the composed matrices are presented to the mold, and automatic means for locking the keyboard mechanism against actuation in the event of

the improper relative adjustment of the two said adjustable members.

12. In a typographical composing and casting machine, the combination of a keyboard mechanism for releasing matrices from their storage magazine, an assembler wherein the released matrices are composed in line and provided with a matrix supporting rail adjustable to active or inactive position in determining the level at which the matrices are composed, a vertically movable transporter adapted to receive the composed line from the assembler and present it to the mold, a stop or filler piece adjustable to active or inactive position so as to arrest said transporter in a raised position or permit it to descend to a normal lower position, and automatic means for locking the keyboard mechanism against actuation when both the matrix supporting rail and the stop or filler piece are in active position.

13. In a typographical composing and casting machine, the combination of a keyboard mechanism for releasing matrices from their storage magazine, an assembler wherein the released matrices are composed in line and provided with a matrix supporting rail adjustable to active or inactive position in determining the level at which the matrices are composed, a vertically movable transporter adapted to receive the composed line from the assembler and present it to the mold, a stop or filler piece adjustable to active or inactive position so as to arrest said transporter in a raised position or permit it to descend to a normal lower position, and means for locking the keyboard mechanism against actuation when both the matrix supporting rail and the stop or filler piece are in active position, said means being actuated by the movement of one of said parts to active position while the other is in active position.

14. In a typographical composing and casting machine, the combination of a keyboard mechanism for releasing matrices from their storage magazine, an assembler wherein the released matrices are composed in line and provided with a matrix supporting rail adjustable to active or inactive position in determining the level at which the matrices are composed, a vertically movable transporter adapted to receive the composed line from the assembler and present it to the mold, a stop or filler piece adjustable to active or inactive position so as to arrest said transporter in a raised position or permit it to descend to a normal lower position, and means for locking the keyboard mechanism against actuation when both the matrix supporting rail and the stop or filler piece are in active position, said means being actuated by the movement of either of said members to active position while the other is in active position.

15. A combination as in claim 10, wherein

the keyboard mechanism includes a series of vertically movable slides controlling the operation of power-operated cam yokes which actuate escapement reeds in effecting the release of the matrices from their storage magazine, and wherein the automatic locking mechanism includes a bar adjustable into and out of locking engagement with said vertically movable slides.

16. A combination as in claim 10 wherein the keyboard mechanism includes a series of vertically movable slides controlling the operation of power-operated cam yokes which actuate escapement reeds in effecting the release of the matrices from their storage magazine, and wherein the automatic locking mechanism includes a bar adjustable into and out of locking engagement with said vertically movable slides, characterized by the fact that the locking bar therein referred to is moved to locking position by the movement of the matrix supporting rail to active position while the first elevator stop or filler piece is in active position, or vice versa.

17. In a typographical composing and casting machine, the combination of an assembler provided with a matrix supporting rail adjustable to active or inactive position, a vertically movable transporter adapted to receive the composed matrices from the assembler and present them to the mold, a stop or filler piece adjustable to active or inactive position so as to arrest said transporter in raised position or permit it to descend to its normal position, and a safety device presenting a movable actuating member arranged to be moved by the movement of the matrix supporting rail to active position while the stop or filler piece is in active position, but not otherwise.

18. In a typographical composing and casting machine, the combination of an assembler provided with a matrix supporting rail adjustable to active or inactive position, a vertically movable transporter adapted to receive the composed matrices from the assembler and present them to the mold, a stop or filler piece adjustable to active or inactive position so as to arrest said transporter in raised position or permit it to descend to its normal position, and a safety device presenting an actuating member arranged to be operated by the movement of either the matrix supporting rail or the stop or filler piece to active position while the other is in active position, but not otherwise.

19. A combination as in claim 17 characterized by the fact that the stop or filler piece is connected to a bar or rod which cooperates with the assembler rail in controlling the operation of the safety device actuating member.

20. A combination as in claim 17 characterized by the fact that the stop or filler piece is connected to a bar or rod which co-

operates with the assembler rail in controlling the operation of the safety device actuating member, and by the further fact that said bar or rod is beveled at its free end and
5 that the assembler rail is also beveled at the adjacent end to cooperate therewith, substantially as shown and described.

In testimony whereof this specification has been duly signed by:

10   LUTHER E. MORRISON.
